DESIGN FOR A BEDSPREAD

Adelph Fassler, Pelham, N. Y., assignor to Harriette A. Lawson, Signal Mountain, Tenn.

Application January 13, 1939, Serial No. 82,332

Term of patent 3½ years

To all whom it may concern:

Be it known that I, Adolph Fassler, a citizen of the United States, residing at Pelham, county of Westchester, and State of New York, have invented a new, original, and ornamental Design for Bedspreads, of which the following is a specification, reference being had to the accompanying drawing, forming part thereof,

The figure of the drawing is a plan view of a bedspread showing my new design.

I claim:

The ornamental design for a bedspread, substantially as shown.

ADOLPH FASSLER.
